UNITED STATES PATENT OFFICE.

JOHN Q. SHERMAN AND ADOLPH F. EUCHENHOFER, OF DAYTON, OHIO, ASSIGNEES TO THE STANDARD REGISTER COMPANY, OF DAYTON, OHIO, A CORPORATION OF OHIO.

MANIFOLDING ATTACHMENT FOR TYPE-WRITERS.

1,254,368.

Specification of Letters Patent. Patented Jan. 22, 1918.

Application filed August 30, 1915. Serial No. 48,015.

To all whom it may concern:

Be it known that we, JOHN Q. SHERMAN and ADOLPH F. EUCHENHOFER, citizens of the United States, and residents of the city 5 of Dayton, in the county of Montgomery and State of Ohio, have invented certain new and useful Improvements in Manifolding Attachments for Type-Writers, of which the following is a full, clear, and exact description, reference being made to the accompanying drawings, forming part of this specification.

Our invention relates to manifolding attachments for typewriters. In devices of 15 this nature, the customary practice in the past has been to provide means traveling with the typewriter carriage for supplying a number of strips of paper. These strips of paper have then been brought around the 20 platen of the typewriter and the duplicate copies made by means of a number of strips of printing ribbon wound in some desired way so as to pass a number of times in front of the printing point on the platen. 25 There is considerable difficulty in these structures in feeding the paper, and it is quite difficult to keep the paper in proper alinement.

It is the object of this invention to do 30 away with the ribbon method of manifolding and to positively feed around the printing platen on the typewriter the manifolding sheets. It is a further object to provide for perfect alinement of the strips of 35 paper by means of toothed feeding wheels which engage in perforations in the paper. It is also an object to provide a carriage for the rolls of manifolding paper which moves easily with the typewriter carriage, and it 40 is further an object to provide means for using carbon paper in connection with the manifolding paper instead of ribbon.

These objects and other advantages which will be noted we accomplish by that certain 45 construction and arrangement of parts to be hereinafter specifically pointed out and claimed.

In the drawings,

Figure 1 is a side elevation of the manifolding devices with the typewriter shown 50 diagrammatically in dotted lines.

Fig. 2 is a rear elevation of the carriage for the manifolding paper.

Fig. 3 is a detail front elevation of the

toothed feeding wheel at the left side of the 55 typewriter.

Fig. 4 is a side elevation of said parts shown in Fig. 3.

Fig. 5 is a top plan view of the stripper.

Fig. 6 is a detail front elevation showing 60 the operative connection between the platen and the feed shaft for the feeding disks.

To the frame 1 of the typewriter is suitably secured the base 2 for the carriage of the manifolding devices. Mounted on this 65 base, which is thicker at the right hand end so as to present an inclined surface from left to right, are the rails 3. The carriage travels on these rails, and has a bottom 4 and frame pieces 5, 5. These frame pieces 70 are divided into two side arms 6, 6, at the sides, and extend upwardly from these arms to form bearings for rollers 8 and 9, and extend forwardly at 10 to mount the carbon paper and various idler rollers as will 75 be hereafter noted. The arms 6, 6, are slotted at 11, 11, for inserting the spindles 12, 12, of two lower rolls of manifolding paper. They are also slotted at 13, 13, to receive the spindles 14, 14, of the two upper rolls 80 of paper, making four rolls altogether.

The film A of paper is brought up from the rearward lower roll around the idler roller 8 above mentioned, brought forward and passed over an idler roller 15 at the extreme upper edge of the forward extension 10 of the side frame pieces. The uppermost of the two rear paper rolls has its film B carried over the idler roller 9, brought forwardly and over the idler roller 16 mounted between the extensions 10. The forward 85 of the two lower rolls has its film C of paper brought up over the idler roller 17 across the frame pieces and this film is brought forward and over an idler 18 extending between 90 the portions 10 of the frame.

Mounted between the idlers 15 and 16 is a roll of carbon paper A'. Between the rolls 16 and 18 is a roll of carbon paper B', and mounted beneath the idler 18 is a third 100 roll of carbon paper C'. These rolls of carbon paper have spindles 19, which extend into bosses 20 at the left hand of the extension 10, and which extend into plungers 21, mounted in the other side of the frame. 105 These plungers have disks 22 mounted around their inner ends and springs 23 maintain these disks frictionally against the car-

bon paper rolls. The plungers have heads 24 by which this spring tension may be relieved for unrolling a portion of carbon paper. The films of paper are brought down 5 and around the platen 25 of the typewriter in the customary manner for typewriter paper. The film D from the forward upper roll of paper passes direct to the printing platen from the carriage.

- 10 In inserting the paper around the platen, the film D is drawn out and the carbon paper C' pulled out and after that on top of the carbon paper the film C is drawn forward and so on, so that between each of the four 15 sheets is a piece of carbon paper. This paper is then inserted around the platen in the ordinary manner, sufficient being drawn out so that the edges of the paper will extend up through the feeding devices to be 20 hereinafter described, and so that the carbon paper will extend up to the printing point on the platen.

For moving the carriage for the manifolding paper, bars 26, 26, are connected to the carriage of the typewriter and pivotally connected to the manifolding carriage at 27, so that when the carriage moves the manifolding carriage will move also. In view of the fact that the manifolding carriage 30 is on an inclined track, the springs in the typewriter carriage will not have to take care of the work in moving the carriage for the manifolding paper, which is a considerable advantage, as in the past it has been 35 found that the typewriter springs are worn excessively and often fail to properly move the typewriter carriage together with the heavy manifolding carriage.

The mechanism for feeding the films of 40 paper by the platen will now be described. Plates 28 are provided, one for each end of the machine, and these plates have a clamp member diagrammatically shown at 29, whereby they are mounted on the cross rod 45 30, which in this make of typewriter carries the paper clamping fingers. The plate has a rearward extension 31, which extends at an angle so as to be bolted to the sides of the carriage. The plate extends forwardly 50 at 32, and provides journals 33 for a cross shaft 34. This shaft has a keyway 35 in it, and on the shaft are a pair of wheels or disks 36, having teeth 37. These disks have their hubs keyed so that they will slide along the shaft 34 to any desired position, and a plate 38 having cutaway portions 39 therein 55 is mounted on the rod 30, these cutaway portions being adapted to receive the teeth. The member 38 is preferably under spring 60 pressure, and its forward end, in which the slots 39 are located, is bent downwardly at 40 so as to lie adjacent to the disks 36. The paper films are brought up around the platen and are provided with a series of 65 perforations spaced apart the distance of the

teeth on the sprockets. The teeth will then engage in the perforations in the paper, and the paper will be held in engagement with these teeth by the member 38. When it is desired to use a narrow width of paper, the 70 disks 36 are arranged at the proper distance apart along the shaft 34, and secured in this position in any desired manner. The cutaway portions 39 are sufficient in number to take care of the usual desired position of 75 these disks 36.

For rotating the disks, the shaft thereof is provided with a pinion 41, which meshes with a pinion 42 on the shaft 43 of the platen of the machine. Thus the usual typewriter mechanism for turning the platen can be used to revolve the shaft 34 and with it the disks 36.

The carbon paper will not be wide enough to be engaged by the teeth on the disks, and 85 it is not intended to have the carbon paper fed to the machine with the films of manifolding paper. Only enough carbon paper is to be drawn off the rolls to extend beyond the printing point on the platen, and the 90 friction on the rolls of carbon paper will prevent its being drawn through with the manifolding paper. It is preferred to disengage altogether the usual friction mechanism against the platen of the typewriter, 95 so that the films of manifolding paper are actuated solely by the two disks heretofore mentioned.

When a portion of the carbon paper is worn out, the operator may, by releasing the 100 tension on the rolls of carbon paper, i. e. by pulling out the plunger 24 (Fig. 2), allow the carbon paper to travel onward slightly with the manifolding paper. The releasing of the plunger 24 will again hold 105 the carbon paper, so that the newly exposed portion thereof will be used until the next change is made.

By providing paper with its edges perforated at regulated intervals in connection 110 with the toothed sprockets or disks, it can be seen that an absolute alignment for manifolding paper is always maintained. On this manifolding device, therefore, rolls consisting of blank forms of various kinds can 115 be filled in, it being only necessary to get the proper lines on the four films in register at the beginning of an operation, whereupon they will remain in complete registry until the paper is torn off. For the purpose of tearing off the paper, a knife 44 is mounted on a plate 44^a, hinged at 44^b on the top of an extension 45 of the member 28 which provides the disk shaft. This plate 44^a extends down at 44^c so as to form a coating, opposed stripper plate in connection with the member 38. It is to be cut away similarly to the member 38.

Various modifications of the general principles of this invention as now described 130

will be readily possible; for example, different methods of arranging the carbon paper could be easily accomplished, without departing from the spirit of the invention; 5 and if desired, the paper feeding means could be used in connection with the manifolding ribbon familiar to the art.

By omitting various modifications and equivalent structures, it is not desired to 10 imply any limitations to specific details of the claims that follow, where the wording of the claims does not negative a broad interpretation.

Having thus described our invention, 15 what we claim as new and desire to secure by Letters Patent, is:—

1. In a manifolding attachment for typewriters, the combination with the platen of the typewriter, of paper mounting means for 20 a plurality of strips of paper located to one side of the platen, and paper feeding means independent of contact with the platen and located to the other side thereof, the same comprising in part rotary toothed members 25 for engagement with successive perforations in the paper, for the purpose described.

2. In a manifolding attachment for typewriters, the combination with the platen, of paper mounting means for a plurality of 30 strips of paper, feeding means for the paper over the platen, adapted to operate on the edge of the paper, means for mounting a piece of carbon paper between the strips of paper, said means adapted to hold the carbon paper immovable while the strips of paper are being fed.

3. In a manifolding attachment for typewriters, having a carriage, and a rotatable platen on the carriage, with means for operating the same, means for feeding a plurality of pieces of paper over the platen comprising toothed members operatively connected to the platen and independent of contact therewith, said members being adapted 45 to successively engage perforations in the paper, and means for adjusting the toothed members lengthwise of the platen for different sized pieces of paper.

4. In a manifolding attachment for typewriters, the combination with the carriage having a revolute platen thereon, of paper mounting means movable with the carriage for a plurality of strips of paper, said mounting means being located to one side of 55 the platen, feeding members located at the other side of the platen, mounted to move with the carriage, and operatively connected to the platen but independent of contact therewith, said feeding means comprising a 60 pair of sprockets adapted to successively engage marginal perforations in the strips of paper.

5. In a manifolding attachment for typewriters having a carriage, means for mounting rolls of manifolding paper so as to move

with the carriage, means for mounting rolls of carbon paper so as to move with the carriage, said latter means arranged so as to feed a strip of carbon paper between the pieces of manifolding paper, means for feeding the manifolding paper without engagement with the carbon paper, and said carbon paper holding means adapted to retain said carbon paper immovable between the manifolding sheets while said manifolding paper 75 is being fed.

6. In a manifolding attachment for typewriters having a carriage, means for mounting rolls of manifolding paper so as to move with the carriage, means for mounting rolls 80 of carbon paper so as to move with the carriage, said latter means arranged so as to feed a strip of carbon paper between the pieces of manifolding paper, means for feeding the manifolding paper without engagement with the carbon paper, and said carbon paper holding means adapted to retain said carbon paper immovable between the manifolding sheets while said manifolding paper 85 is being fed, said carbon paper holding 90 means adapted to be released at will to permit the carbon paper to be frictionally drawn along with the pieces of manifolding paper.

7. In a manifolding attachment for a typewriter having a carriage and a rotatable platen, means for positively feeding a plurality of pieces of paper by the said platen comprising toothed members, means for operating the same, said toothed members 100 adapted to engage in and hold the paper in perfect alinement while feeding the same, and a stripper device to lift the paper from the toothed members.

8. In a manifolding attachment for a typewriter having a carriage and a rotatable platen, means for positively feeding a plurality of pieces of paper by the said platen, said paper having graduated perforations at its edges, comprising toothed members, 110 means for operating the same, said toothed members adapted to engage in and hold the paper in perfect alinement while feeding the same, and a stripper device to lift the paper from the toothed members.

9. In a manifolding attachment for a typewriter having a carriage and a rotatable platen, means for positively feeding a plurality of pieces of paper by the said platen comprising toothed members operatively connected to the platen, said toothed members adapted to engage in and hold the paper in perfect alinement while feeding the same, and a stripper device to lift the paper from the toothed members.

10. In a manifolding attachment for a typewriter having a carriage and a rotatable platen, means for feeding a plurality of pieces of paper by the said platen, comprising toothed members operatively connected 130

4
to the platen and adapted to engage the paper, and a stripper device to lift the paper from the toothed members.

11. In a manifolding device for typewriters, in combination with the platen of a typewriter, and a carriage therefor, a shaft located beyond the platen, toothed members

adjustable along the shaft, and a plate having a series of slots for clearance of the toothed members, said plate being adapted to hold perforated manifolding sheets against the toothed members.

JOHN Q. SHERMAN.
ADOLPH F. EUCHENHOFER.
